UNITED STATES PATENT OFFICE.

EDWIN J. VICKERS, OF NEW PHILADELPHIA, OHIO.

ACCOUNT-FILE.

No. 881,363.

Specification of Letters Patent. Patented March 10, 1908.

Application filed June 5, 1907. Serial No. 377,427.

To all whom it may concern:

Be it known that I, EDWIN J. VICKERS, a citizen of the United States, residing at New Philadelphia, in the county of Tuscarawas and State of Ohio, have invented a new and useful Account-File, of which the following is a specification.

This invention relates to a device for filing in an accessible and compact form account 10 slips contained in numbered trays, a keyboard to be used in connection with said trays and the numbers thereon, and an indexed file for holding such letters, bills, etc. as are not suitable for admission to the trays.

15 The main object of the invention is to provide a file holder in which a large number of file trays for containing numerous account slips may be mounted in compact form and occupy a comparatively small space, to 20 which accounts access may be gained without any appreciable loss of time.

Another object of the invention used in connection with the file holder relates to a key of the accounts contained in the file 25 trays which enables the person keeping the file to know by a mere glance at the key whether any one having an account with him has paid up, paid on account, or is delinquent in his payments.

30 A further object of the invention refers to an indexed file in which may be kept, alphabetically arranged, all letters, bills, receipts, etc. which are not suitable for admission to the trays or files.

35 A suitable casing is provided to protect the account slip trays and the indexed files, while the key is placed on one or two tablets hinged to the base of the casing and adapted to fold up against the ends of the same and 40 secured thereto by a suitable latch, the whole presenting a neat and attractive appearance.

The account file may for convenience be secured to the top of a case in which is fitted a money drawer and writing board.

45 With these and other objects in view, the invention further consists in certain novel construction, combination and arrangement of parts hereinafter described and definitely pointed out in the claims.

50 To fully illustrate and make clear the invention, attention is called to the accompanying drawings, in which,

Figure 1 is a perspective view of the account file partly open to expose certain elements of the invention which would otherwise be hidden from sight. Fig. 2 is a verti-

cal longitudinal sectional view through the center of the account file closed. Fig. 3 is a cross sectional view on the line 3—3, Fig. 2. Fig. 4 is a face view of a part of the key of 60 accounts mounted on a tablet. Figs. 5 and 6 are top and bottom plan views respectively of an account slip file or tray. Fig. 7 is a cross sectional view on the line 7—7, Fig. 5. Fig. 8 is a detail view of a part of a tray and 65 its supporting arm. Fig. 9 is a view of a tray knob.

Similar reference numerals are used on all the figures to designate the same parts.

As a support or base for the account file, 70 there may be provided a box or case 1 in which is fitted a money drawer 2, and a writing board 3 below the money drawer. This support, however, is only a convenience, as the file holder may be attached to any other 75 form of base demanded by the user.

Rigidly secured to the base 1 are two upright arms 4 and 5 suitably spaced to admit a horizontal cylinder 6 fixed to a shaft 7 journaled in the aforesaid upright arms 4 and 5. 80

Projecting radially from the periphery of the cylinder 6 are a plurality of arms 8 arranged in two series in planes perpendicular to the axis of the cylinder. Each arm has preferably at its inner end a foot 9, fixed in 85 any suitable manner to the cylinder 6, and a central slot 10 extending from said foot to a point near its outer end where it terminates in a cross slot 11, the two slots together resembling a long letter T (see Fig. 6). 90

Slidably mounted on each arm 8 is a file tray 12 having upturned sides and front end, the latter 13 having an upward curve to afford room for attaching thereto at its center, a knob 14. The outer face of the knob 95 has the number of the file tray placed thereon; its stem, passing through the front end of the file tray and rotatable therein, carries within the tray a finger 15 of sufficient length to extend through a slot 16 in the tray and 100 into the cross slot 11 in the end of the arm 8. From this it will be observed that when the finger is turned down the file tray will be locked to the arm and cannot slip off even when in its lowermost position. The number 105 of the file is placed on the knob in such relation to the finger 15, that when the number is upright the finger will be locked to the arm. A spring arm 17 is attached to the inner end of the file tray and extends forwardly to hold the account slips in place so that they will not fall out when the cylinder 110

is rotated. For convenience the file trays with even numbers are placed in one series and those with odd numbers in the other series. On the under side of the file tray are 5 attached two guide plates 18 between which and the bottom of the tray the arm 8 slides as the file trays are withdrawn and returned. As an additional guide to the tray, a stop plate 19 depends therefrom through the slot 10 in the arm and is provided with lateral extensions below said arm, as clearly shown in Fig. 6.

The cylinder 6 and the slidable file trays 12 thereon are inclosed within a sheet metal 15 casing 20 having a straight vertical back and a curved top and front concentric with the cylinder and extending a very short distance outside the file tray knobs 14. Attached to the front of the casing and a little below its 20 center is an inclined shelf or rest 21, its outer end supported by a curved front plate 22 resting on the base 1. The upper surface of the shelf is in a plane passing through the axis of the cylinder, so that when the file 25 trays are withdrawn for use, they rest flatly on the shelf. In the front of the casing 20 are two parallel slots 23 and 24 extending from near the top of the casing to a point below the shelf or rest 21, which latter, as well 30 as the curved front plate 22 are also slotted at 25 and 26. The slots 23 and 24 expose the knobs 14 of the file trays and are sufficiently wide to admit the fingers for turning the file holder, but too narrow to permit the 35 files being withdrawn except at the level of the shelf 21 where the slots are widened laterally at 27 and 28 sufficiently to allow the withdrawal of a tray from either or both series.

40 The file trays and holder are inclosed within the casing 20 by partitions 29 and 30 placed within the ends of the casing near the uprights 4 and 5. The left end of the casing is in this type permanently closed by an end 45 plate 31, but the right end is covered by a door 32 hung to the back of the casing by a hinge 33 and provided on its edge with a flange 34 having an outline similar to the outline of the casing. Within the space between 50 the partition 29 and the door 32 is pivoted to said partition an indexed file 35 formed of a number of pivoted leaves 36 adapted to fold one upon another and be fastened by a latch 37 and be opened out as in Fig. 1 to insert or 55 remove a paper from the file. Each leaf has attached to it a plurality of spring arms 38 to hold the papers filed, and an index on its outer edge. When the file 35 is folded within the space 39 and the door 32 closed, the 60 flange 34 of the door passes over the edge of the casing and is held against accidental opening by a latch 40 on the door engaging with a depression 41 on the casing. A finger piece 42 is applied to the door for opening and 65 closing it.

As thus far disclosed all that is necessary to obtain an account slip is to rotate the file holder by means of the fingers on the knobs until the desired number is brought opposite one or the other enlarged slot 27 or 28. Then, 70 by pulling on the knob 14 the file tray 12 will be withdrawn through the slot as far as possible and rest on the shelf 21 in convenient position for carefully examining its contents. As long as the tray remains in open position 75 the file holder cannot be rotated, the tray 12 locking it fast at 27 or 28, but when the tray is pushed in, the file holder may then be once more revolved. The absolute withdrawal of the tray is prevented by the stop 80 plate 19 on the tray striking the outer end of the slot 10 formed in the arm 8 and being arrested thereby.

The knobs 14 contain numbers only, as hereinbefore stated, and unless the operator remembers the numbers temporarily attached to the names of the numerous persons it will be very difficult to find the file tray containing any one person's account. To obviate this difficulty and at the same time show the condition of any account as to whether it has been paid up, anything paid on account, or if it be delinquent, a key is provided which, for convenience, is divided into two parts, placed on tablets 43 and 44, pivoted to opposite ends of 95 the casing at the bottom so that they can be folded up close against the ends and secured by a spring catch 45 at the top of the casing which is curved on the same radius as said top. The key is divided similarly to the 100 numbered file trays; that is, the even numbers on one tablet—say the right hand one—and the odd numbers on the other tablet. The even number tablet 43 is pivoted to the outside of the door 32 and swings out with it, 105 the spring latch 45 for holding the tablet closed being attached to the door flange.

The arrangement of each key tablet is the same, and therefore a description of one will serve for both. Referring to Fig. 4 on which 110 the left or odd number tablet is represented, there is disclosed a series of parallel horizontal lines 46 equal in number to one-half the file trays in the left series of files on the cylinder 6. These horizontal lines are divided centrally by a vertical line 47 into two sections. On the left of each section are vertical lines forming two narrow columns 48 and 49. A similar line on the right of each section forms a third narrow column 50. In 115 the two columns 48 are placed the odd numbers corresponding to the odd numbered file trays. In the broad spaces between the columns 49 and 50 are written the names of persons whose account papers are in the file 120 trays bearing the same number. The column 50 is left blank for future written insertions. The columns 49 are reserved for markers of different colors, shapes or other 125 means of distinguishing in a moment the kind 130

employed for showing the condition of the account. In the present instance the markers consist of headed pins which are pushed into the tablet in the column 49 on the same line with, but between, the name of a person and his number. The markers here employed are distinguished by colors, for instance, those 51 have red heads and indicate that the account of the person on the same line is paid up; blue heads 52 show that the accounts of persons on the same line have been in part liquidated, while the yellow pins 53 denote delinquent accounts. Additional pins of the several colors are stored near the bottom of the tablet, and at 54 are representations of the distinguishing characteristic of each variety of pin followed by a short description of the use to which it is put. A few additional horizontal lines are placed below the numbered lines 55 for writing upon. At one side of the key columns is fastened a pocket 56 in which may be placed delinquent miscellaneous accounts to remain there until they can be placed in the proper file tray or other suitable place after notifying the persons to whom they belong of the condition of their account.

An account file of this type is very useful and a time saver in all forms of business and where a great number of debit and credit accounts are kept; one series of file trays may be used for debits and the other side for credit entries. By means of the key a business man can ascertain at a moment's notice the condition of his business, the reliability of those who deal with him and whether it would be safe to continue their credit. The device is simple and can be manufactured at a comparatively small cost, thus enabling it 40 to be placed in the hands of small dealers.

Having thus described the invention, what is claimed is:

1. An account file comprising a rotatable cylinder, a plurality of fixed arms projecting radially from its periphery, and a file tray slidably mounted on each of said arms.
2. An account file comprising a rotatable cylinder, a plurality of fixed arms projecting radially from its periphery in two series, and 50 a file tray slidably mounted on each of said arms.
3. An account file comprising a rotatable cylinder, a plurality of fixed arms projecting radially therefrom in two series parallel to each other and in planes perpendicular to the axis of the cylinder, a file tray, slidably mounted on each of said arms, and means for locking each of said trays to its respective arm.
4. An account file comprising a rotatable cylinder, a plurality of fixed arms projecting radially therefrom, in two parallel series, a 60 file tray slidably mounted on each arm, and

a casing for said file trays having a slotted opening in its front opposite each series of file trays but of less width than said trays except at one point where it expands to the width of said trays.

5. An account file comprising a revoluble file holder having a plurality of slidable file trays, a casing for said file holder having a curved front with a vertical slot in the curved front of said casing opposite to but narrower than said file trays, and a shelf projecting from said casing front below a lateral extension of said slot, said extended opening being of sufficient size to permit one of said file trays to pass through.

6. An account file comprising a revoluble file holder having a plurality of slidable file trays arranged in two parallel series, a casing for said file holder having a slotted opening opposite each series of file trays of sufficient size to permit a single file tray to pass through, an indexed file within one end of said casing, and a door hinged to said side for inclosing said indexed file.

7. An account file comprising a revoluble file holder having a plurality of radially slid- 90 able file trays each provided with an identi- fying mark differing from all the others, a casing for said file holder, a tablet hinged to said casing and adapted to fold downwardly to a horizontal position, and a key to said identifying marks on said tablet. 95

8. An account file comprising a revoluble file holder having a plurality of radially slid- 100 able file trays arranged in two parallel series, each tray being numbered differently, a cas- ing for said file holder, a tablet hinged on each side of said file holder and adapted to fold upwardly against the casing or to a horizontal position, numerals in columnar form on each tablet corresponding to the numerals on the file trays contained in the adjacent series, 105 a space for a name opposite each number, and a plurality of sets of markers each one of which when placed opposite a name or number will convey by its distinguishing character certain information. 110

9. An account file comprising a revoluble file holder having a plurality of fixed radial arms, a file tray adapted to slide longitudinally on each arm, and a knob pivoted on the front of said file tray and provided with a 115 finger within the file, said finger adapted when turned to lock the file tray to the fixed arm within the casing.

In testimony that I claim the foregoing as my own, I have hereto affixed my signature 120 in the presence of two witnesses.

EDWIN J. VICKERS.
